(57) **CLAIM**

The ornamental design for a rear view mirror indicator, as shown and described.

DESCRIPTION

FIG. 1 is a top perspective view of a rear view mirror indicator showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a partial enlarged view of FIG. 2.

The broken lines shown in the figures are for the purpose of illustrating environment and form no part of the claimed design.

The long dash broken lines in FIG. 2 and FIG. 8 indicate the detail view and form no part of the claimed design.
